EVAPORATOR UNIT

John H. Benson, Salem, Ohio, assignor to Mullins Manufacturing Corporation, Salem, Ohio, a corporation of New York

Application February 2, 1933, Serial No. 654,899

10 Claims. (Cl. 62—126)

This invention relates to an evaporator unit, and has to do particularly with a sheet metal cooling unit provided with a suitable header of the type shown in Reissue Patent No. 18,182 of

5 September 8, 1931.

In sheet metal evaporators of this type, it is usually desirable to use a relatively small quantity of liquid refrigerant and hence to construct the evaporator with a relatively small header.

10 It is also desirable to extend the side walls of the header radially therefrom so as to weld the side walls at a point very closely adjacent the header. The reducing of the diameter of the header is usually limited because with a relatively small 15 header a slight variation in level of the refrigerant would uncover the side passageways. Other disadvantages in this type of sheet metal evaporator relate to the enameling wherein the subjecting of the header to a pressure frequently 20 caused a slight movement of the metal at the point where the side walls joined the header with the result that the enamel often chipped or peeled.

It is an object of the present invention to overcome any possibility of oil logging due to a variation in level in the header and to make it possible to use a header of relatively small capacity.

A further object of the present invention is to strengthen the inner shell at the juncture of the 30 side walls and the header to prevent the porcelain enamel coating from chipping off the evaporator adjacent the header. This result is effected by using relatively short beads or bullets designed to break up the flat areas and reinforce 35 the header at the points of contact with the header halves, or otherwise at the point where the entire structure is subjected to the greatest stress.

A still further object of the invention is to 40 minimize disturbance of boiling refrigerant entering the header from the side walls; by substantially doubling the area of the passageways as they enter the header restriction is minimized and this results in much less disturbance. Other 45 novel features of the invention will be more clearly set forth in the specification and claims.

In the drawings:

Fig. 1 is a front elevation of a sheet metal evaporator embodying the present invention.

50 Fig. 2 is a sectional view taken on line 2—2 of Fig. 1, showing the increased size of the passageways resulting from the beads or bullets.

Fig. 3 is a sectional view taken on line 3—3 of Fig. 2 and showing in detail the preferred 55 location of the bullets.

Fig. 4 is a sectional view taken on line 4—4 of Fig. 2 and showing one pair of bullets in elevation.

Fig. 5 is a sectional view taken on line 5—5 of Fig. 3 showing the method of fabricating the 5 manifold for connecting the ends of the spaced bullets.

Fig. 6 is a sectional view taken on line 6—6 of Fig. 3 showing the manifold in elevation and the 10 bullets in cross section.

Fig. 7 is a sectional view taken on line 7—7 of Fig. 3.

The present invention is particularly applicable to evaporators of the type wherein the side walls are formed integral with the header walls, 15 but it will be understood that my reinforcing bullets are equally adaptable to all evaporators having headers and side walls leading therefrom regardless of whether said side walls are welded to the header or formed integrally therewith. 20

In the illustrated embodiment of the invention the evaporator is shown as consisting of a header 2 formed of two sections 3 and 4. Side walls 5 and 6 are reinforced by means of suitable corrugations 7 and these corrugations act as passageways for distributing the liquid refrigerant from the header around the sharp freezing chamber. Longitudinal manifolds 8 are formed longitudinally of the header and spaced therefrom and bead members or bullets are fabricated 30 as at 9 to extend from said manifolds inwardly and radially to said header.

The evaporator may be of the type where the outer shell, including the portion 3 of the header, and the corrugated side walls are fabricated 35 in one piece with the side walls extending radially outwardly as shown at 10 in dotted lines in Fig. 1, and the inner shell and corresponding side walls formed to complementally fit with the outer shell so that the side walls may be welded together in between the corrugations and then bent to the shape shown in Fig. 1.

Short beads or bullets 11 are formed as a part of the inner shell and at the point where the side walls 5 and 6 join the portion 4 of the header, 45 as best shown in Fig. 3. These bead members 11 may be of any shape and may join the header at any point in its circumference, but in the preferred form the bullets are substantially semicircular, as best shown in Fig. 6 and are substantially the same shape as the corrugations 7 formed in the outer shell of the evaporator. The manifolds 12 are formed in the outer shell and extend parallel to the header and closely adjacent thereto so that the side walls, as they leave 50

55

the header, are reinforced and they also make it possible to weld in between each corrugation and in between the manifold and the header as at the point 13 so as to provide the greatest 5 amount of strength for the header at the point subjected to the greatest stresses or, in other words, at the point most liable to rupture.

By using the bullets 11 in the particular embodiment shown in Fig. 3, it will be seen that the 10 level of the refrigerant may drop to the point 14 before the oil will seal off the corrugations 7 from the header. In other words, by using the bullets of the design shown in Figs. 3 and 4, I have provided the distance between the dotted lines 15 15 and 14 as an extra height to take care of refrigerant level variation in the header to prevent oil from running down into the corrugations. This bullet structure thus permits the header 2 to be made considerably smaller and thus requiring a 20 less amount of refrigerant which is a condition toward which most refrigerator manufacturers are striving.

After the welding together of the two parts to form the top shell or header and the downwardly 25 extending shells the evaporator is usually enameled and then after enameling and before use it is subjected to a pressure test. While frequently the pressure applied to the interior of the evaporator causes the short portion which joins the 30 header with the inner shell to straighten out and flatten, the welding in between the corrugations prevents any great straightening out but, nevertheless, a small flattening occurs which has heretofore resulted in much chipping. By the adding 35 of the short beads or bullets at this very important point of the evaporator I have stiffened the header where it meets the radial side walls and provided a structure which will resist the chipping or "peeling" action heretofore caused by 40 the straightening out of this angle. The bullets also transmit some of the stresses to the second row of spots on the other side of the manifold 12 away from the header.

As will be seen by comparing Figs. 6 and 7, the 45 adding of the bullets or short beads between the manifold and header in the inner shell substantially doubles the cross sectional area of the passageways entering the header, thus materially minimizing any disturbance due to boiling of the 50 refrigerant entering the header from the passageways.

In the embodiment illustrated in Fig. 2 the entire evaporator is shown as being formed of two pieces with flanges 16 and 17 at the front 55 and back. This type of evaporator is particularly adaptable for use with a high side float or capillary tube and the inlet and outlet to and from the header may be located at any desired points in accordance with standard practice.

60 What I claim is:

1. A sheet metal evaporator comprising outer and inner shells fabricated to each form a portion of a header and laterally and downwardly depending side walls, one of said laterally extending walls being embossed to reinforce the same and provide passageways in communication with and extending into the header, and relatively short beads formed in the other wall at the region where it connects into the header 65 whereby to lower the possible level of the refrigerant in the evaporator before uncovering the passageways of the side walls.

2. A sheet metal evaporator comprising outer and inner shells fabricated to each form a portion of a header and laterally and downward-

ly depending side walls, one of said side walls being embossed to reinforce the same and provide passageways leading from the header, and beads formed in the other side wall and extending from the header a relatively short distance outwardly therefrom, some of said beads being in alignment with the embossed portions of the outer shell entering the header. 5

3. A sheet metal evaporator comprising outer and inner shells fabricated to each form a portion of a header and radially and downwardly depending side walls, the upper of said side walls being embossed to reinforce the same and provide passageways extending from the header, and beads formed in the lower side walls and extending from the header a relatively short distance outwardly therefrom, some of said beads being in alignment with the embossed portions of the outer shell entering the header. 10

15 4. An enameled sheet metal evaporator comprising a header and outer and inner shells extending therefrom and directly connected thereto, the outer shell having embossed portions leading from points adjacent the header and forming passageways, and the inner shell having a plurality of relatively short embossed portions at the region where it joins the header and positioned opposite to and in alignment with some of said embossed portions whereby to reinforce the header to lower the effective refrigerant level and prevent peeling off of the enamel when the evaporator is subjected to pressure. 20

25 5. An enameled sheet metal evaporator comprising outer and inner shells fabricated to each form a portion of a header and laterally and downwardly depending side walls, the outer side wall being embossed to provide passageways extending from the header, a manifold formed in said outer wall and extending transversely of the passageways at a point adjacent the header, and 30 short embossed beads formed in said inner wall and extending from said manifold inwardly to the header, said beads lowering the effective refrigerant level of the header and reinforcing the evaporator to prevent chipping of the enamel 35 when the evaporator is subjected to pressure. 40

45 6. An enameled sheet metal evaporator comprising outer and inner shells fabricated to form a two piece evaporator, a header, and radially and downwardly depending side walls, the outer side 50 wall being embossed to provide passageways extending from the header, a manifold formed in said outer wall and extending transversely of the passageways at a point adjacent the header, and short embossed beads formed in said inner wall and extending from said manifold inwardly to the header, said beads lowering the effective refrigerant level of the header and reinforcing the evaporator to prevent chipping of the enamel 55 when the evaporator is subjected to pressure. 60

7. A sheet metal evaporator comprising outer and inner shells fabricated to each form a portion of a header and laterally and depending side walls, the outer side wall being corrugated to form passageways extending from the header and the inner wall being generally flat, the walls being welded together on lines between the corrugations, and relatively short beads formed in the inner wall at the region where it joins the header and registering with the corrugations whereby to lower the lowermost effective refrigerant level and to increase the area of the passageways immediately as they enter the header. 65

70 8. A sheet metal evaporator comprising a header, parallel inner and outer shells directly con- 75

nected with said header for distributing liquid refrigerant therefrom, said shells having angularly positioned portions defining at least two walls of a sharp freezing chamber, beads formed in one of said shells and extending from said header for substantially the continuous length of said two walls, and relatively short beads formed in said other shell and extending outwardly from the header and spaced longitudinally of the header.

9. A sheet metal evaporator of the flooded type comprising an outer one piece shell fabricated to form a centrally positioned arcuate depression extending substantially but less than the width of the shell and corrugations extending laterally from each side of said arcuate portion and terminating short of the ends of the shell, an inner one piece shell fabricated to form a centrally positioned header portion adapted to cooperate with said arcuate portion on the outer shell to form a header, laterally extending walls cooperating with the corrugated walls of the outer shell, said cooperating walls of the inner and

outer shell being bent to form a sharp freezing chamber, said shells being fabricated to form matching flanges extending continuously around the complete periphery of the shells, the shells being sealed together by a substantially continuous weld extending around said flange, and relatively short beads formed in the inner shell and extending transversely from the header portion in said inner shell and positioned opposite to the corrugations in the outer shell.

10. A sheet metal evaporator of the flooded type comprising a header, walls extending laterally from said header and shaped to form a portion of a sharp freezing chamber, said walls being directly connected to the header walls and one of said walls being corrugated to form passageways leading from the header, said walls being welded together in the spaces between the corrugations, and relatively short beads formed in the other wall at the region where it enters the header and cooperating with some of said passageways.

JOHN H. BENSON.
